CLAIM

The ornamental design for a wall-mounted network console, as shown and described.

DESCRIPTION

FIG. 1 is a top right perspective view of a wall-mounted network console in accordance with the present invention; FIG. 2 is a front plan view thereof; FIG. 3 is a back plan view thereof; FIG. 4 is a top elevation view thereof; FIG. 5 is a bottom elevation view thereof; FIG. 6 is a right side elevation view thereof; FIG. 7 is a left side elevation view thereof; FIG. 8 is a back perspective view thereof; FIG. 9 is an alternative front plan view; and, FIG. 10 is a front perspective view of an alternative position thereof.

The broken lines shown in the drawings are for the purpose of illustrating environmental structure and form no part of the claimed design.

1 Claim, 10 Drawing Sheets
